WRAPPER AND PACKAGED ARTICLE

Clarence B. Stiner, New York, N. Y., assignor to Sylvania Industrial Corporation, Fredericksburg, Va., a corporation of Virginia

Original application August 12, 1936, Serial No. 95,518. Divided and this application September 20, 1937, Serial No. 164,622. In Canada August 3, 1937

9 Claims. (Cl. 131—11)

The invention relates to wrappers and in particular to packaged cigars and wrappers for the same, and to correlated improvements designed to enhance the utility of containers for cigars.

When moistureproof Cellophane first appeared on the market, the tobacco industry immediately adopted the use of this material for wrapping and packaging cigars. At first it was proposed to hermetically seal the cigars in a tube or wrapper constructed of moistureproof Cellophane to preserve the moisture content in the tobacco. The hermetical seal was soon abandoned because it was found that the moisture favored the development of a mold or fungus growth on the cigar. This undesirable growth was caused by increasing temperatures which in turn caused the tobacco to give off water and carbon dioxide. Inasmuch as the cigar could not breathe through the wrapper, the water evolved condensed on the inner surface of the wrapper giving rise to an extremely moist atmosphere which initiated the above mentioned growth.

The next proposal tried by the industry was to seal the ends of the Cellophane tube or wrapper in spaced areas only, thus permitting the cigar to breathe. The use of a breathing seal solved the problem of eliminating mold or fungus growths. The next serious disadvantage of using Cellophane was that the interior as well as the exterior of the cigar was not free to absorb the aroma given off by the cedar wood, from which most cigar boxes are made, notwithstanding the use of breathing seals. It is highly desirous to subject a cigar both internally and externally to the action of an essential oil such as cedar to flavor the cigar and impart a pleasing aroma thereto. However, the circulation of the aroma in a cigar box is impeded due to the pressure and compactness under which cigars are usually packed in the box. Moreover, whatever circulation there might be, only the outer surfaces of the cigars were subjected to the aroma.

The general object of the invention is to obviate the foregoing and other disadvantages of the prior practice in packaging cigars.

The specific object of the invention is to package cigars in a manner as to promote the circulation of beneficial aromas into the cigars.

Another object of the invention is to provide Cellophane wrappers and containers for cigars which enable the cigar to absorb beneficial aromas within the body of the cigar.

Other objects of the invention will in part be obvious and will in part appear hereinafter.

The invention accordingly comprises a product

possessing the features, properties, and the relation of components which will be exemplified in the product hereinafter described and the scope of the invention will be indicated in the claims.

According to the invention, there is provided a wrapped cigar and a wrapper therefor having a perforation at the end to expose the tuck end of the cigar to permit breathing and absorption of beneficial aromas by the filler of the cigar.

For a fuller understanding of the nature and objects of the invention, reference should be had to the following detailed description taken in connection with the accompanying drawing, in which:

Fig. 1 is a perspective view of a plicated cigar tube of the invention.

Fig. 2 illustrates, in a perspective view, a cigar wrapper of the invention as it appears around a cigar.

Fig. 3 illustrates, in cross-section, the combination of a wrapped cigar of the invention in a container.

Fig. 4 is a perspective view of a package of the invention showing the relation between the tuck ends of the cigars to the outer container.

The cigar wrapper may be made according to any suitable process and may have any desired cross-sectional shape, but it will be hereinafter referred to generically as a tube or tubular body. The wrapper may be formed about the cigar as by leading a relatively narrow strip of material into a machine which forms and encloses a cigar within a tube of the material. The tubular body may be preformed as by making a tube from a strip of material and closing one end only. In this latter construction, the cigars are slipped into the closed end tubes which may be plicated or not and the other end sealed to completely enclose the cigar.

The individual cigar wrappers may be composed of any suitable material such as Cellophane, metallized Cellophane, cellulose ethers, cellulose esters, gelatin, casein, synthetic resins, rubber, rubber derivatives, metal foil, glassine paper or any combination of these sheet materials whether laminated or merely superimposed and/or coextensive with each other or not. These materials may be coated and/or impregnated with any suitable moistureproofing, waterproofing and/or aroma-imparting agents or compositions.

The outer container or box may be composed wholly or in part of suitable aroma-evolving material such as cedar wood or any suitable mate-

rial naturally carrying or being impregnated with an essential oil which would impart a pleasing and beneficial flavor to cigars.

Referring to the drawing, Fig. 1 illustrates a preformed cigar tube 1 having a closed end 2 and an open end 3, plicated walls 4, a longitudinal seam 5 and a perforation 6 positioned in such a manner that when the walls 7 are brought together and the end 3 bent downwardly on a line 8 and folded on the line 9 the perforation 6 will lie about the longitudinal center line of the tube 1 and thus expose the tuck end of a cigar that may be disposed within the tube.

In Fig. 2 there is shown a cigar 10 (shown in dotted lines) having a head end portion 11 and a tuck end portion 12. The cigar 10 is disposed within a wrapper 13 comprising a tubular body 14 having a seam 15, its extremities formed into flaps 16 and 17 folded over against the body portion, as shown, and may be sealed thereto if so desired. The flap 16 is provided with a perforation 18 which surrounds the tuck end portion 12 of the cigar 10, thus exposing said tuck end. From this structure, it may be seen that the atmosphere surrounding the tuck end 12 has free access to the interior of the cigar thus permitting the cigar to breathe and absorb any substances which may be present in the immediate atmosphere.

Fig. 3 illustrates the wrapped cigar 10 of Fig. 2 positioned in an aroma-evolving container 19. The exposed tuck end 12 of the cigar 10 substantially abuts the side wall 20 of the container 19. It is also within the purview of this invention to perforate the cigar wrapper at both ends. Moreover, the cigar may likewise have both ends cut to expose the filler and thereby further promote the circulation of the aroma-laden atmosphere within the filler.

In Fig. 4 there is shown a complete cigar package of the invention comprising a plurality of individually wrapped cigars 21 positioned within a container 22 which is composed of a material adapted to give off the desired aroma. The tuck end portion 12 of one of the cigars is indicated by dotted lines to illustrate the cooperating relationship between this exposed end of the cigar and the aroma-evolving side walls of the container 22.

It is clear from the construction afforded by this invention that the atmosphere bearing the aroma evolved by the containers 19 and 22 is free to circulate and penetrate the interior as well as the exterior of the cigar. The interior or filler portion of a cigar is composed of several substantially continuous tobacco leaf layers which normally extend longitudinally with respect to the cigar. Due to this structure, the aroma-laden atmosphere easily and freely communicates with the filler leaves by way of the entrance provided through the opening at the tuck end of a cigar.

The individual cigar wrappers may be perforated in any suitable manner and during any stage of production. The perforation may be of any desired size or shape or a plurality of smaller perforations may be provided. The perforating step may take place (1) while the material is in strip form, or (2) after formation of a tube, or (3) after the wrapper has been applied to the cigar. It is within the purview of this invention to include any individually wrapped cigar or

packages of two or more cigars having the tuck end of each cigar exposed for the purpose herein disclosed.

While any suitable packaging materials may be employed in carrying out this invention as hereinbefore mentioned, it is preferred to employ non-fibrous, cellulosic materials, especially Cellophane, for the individual cigar wrappers and to use cedar wood as the aroma-evolving material.

Since certain changes may be made in the above product and different embodiments of the invention could be made without departing from the scope thereof, it is intended that all matter contained in the above description or shown in the accompanying drawing shall be interpreted as illustrative and not in a limiting sense.

This application is a division of my copending application Serial No. 95,518, filed August 12, 1936.

Having described my invention, what I claim as new and desire to secure by Letters Patent is:

1. As an article of manufacture, a wrapped cigar comprising, in combination, a cigar having a tuck end and a wrapper enclosing the cigar and having a perforation extending through the wrapper adjacent the tuck end of the cigar.

2. A product of the class described, a wrapped cigar comprising, in combination, a cigar having a tuck end and a pellicle of a non-fibrous, cellulosic material substantially enclosing the cigar, said pellicle having a perforation adjacent the tuck end of the cigar.

3. A product of the class described, a wrapped cigar comprising, in combination, a cigar having an end cut to expose the filler and a Cellophane wrapper having a perforation at one end thereof positioned adjacent said cut end of the cigar.

4. A product of the class described, a cigar wrapper comprising a tubular container having closed ends, one of the ends being perforated to expose the tuck end of a cigar that may be disposed therein.

5. A product of the class described, a cigar wrapper comprising a tubular body of Cellophane having closed ends, one of the ends being perforated.

6. A product of the class described, a cigar wrapper comprising a tubular body of a cellulose ester having closed ends, one of the ends being perforated.

7. A product of the class described, a cigar wrapper comprising a tubular body of metal foil having closed ends, one of the ends being perforated.

8. A product of the class described, a wrapper for cigars comprising a tubular body of Cellophane closed at one end and having a perforation spaced from the open end so that when the open end is closed by folding the tube upon itself, the perforation will lie substantially about the longitudinal center line of the tubular body.

9. An article of manufacture comprising a cigar, an individual and exposed wrapper completely surrounding and snugly encasing the cigar, said wrapper being provided with openings extending through the wrapper to permit breathing to take place between the interior of the cigar and the atmosphere adjacent the exterior of the wrapper.
